SPIRAL BLADE FAN

Filed April 26, 1929

Owen H. Spencer
Inventor

UNITED STATES PATENT OFFICE

OWEN H. SPENCER, OF INDIANAPOLIS, INDIANA

SPIRAL BLADE FAN

Application filed April 26, 1929. Serial No. 358,366.

- This invention relates to fan structures and particularly to the blast fan variety, and one feature of the invention is the provision of a combined fan hub and blades therefor.
- 5 A further feature of the invention is the provision of blades so arranged that a vacuum will be formed during the rotation of the blades, thus increasing the volume of air to be picked up by the succeeding blade.
- 10 A further feature of the invention is in so constructing the blades that they will assume a spiral outline from their inner to their outer ends about one edge thereof, whereby the blast of air will be forced from the inner 15 towards the outer ends thereof and the volume of air gradually increased from the inner to the outer ends of the blades, by which arrangement the ends of the blades will be fed by the remainder of the blade.
- 15 Other objects and advantages will be hereinafter more fully set forth and pointed out in the accompanying specification.

In the accompanying drawings which are made a part of this application,

- 20 Figure 1 is a fragmentary plan view of the fan structure.

Figure 2 is an edge elevation thereof with parts in section and showing the different contours of the blade in full and dotted lines, 25 corresponding to Figures 3 to 6 inclusive.

Figure 3 is a sectional view as seen on dotted line 3—3, Fig. 1.

Figure 4 is a section on line 4—4, Fig. 1.

Figure 5 is a section on line 5—5, Fig. 1, 30 and,

Figure 6 is a section on line 6—6, Fig. 1.

Referring to the drawings, the numeral 1 indicates the hub of the fan structure, which is preferably substantially hollow and semi-40 globular, having a bearing sleeve 2 centrally thereof, for the reception of a shaft.

Formed on the periphery of the hub 1, and preferably integral therewith, are blades 3, the inner edges 4 thereof extending substantially in a straight line from end to end, while the opposite edges 5 thereof are curved substantially coincident to the curvature of the outer face of the hub 1, such curvature imparting a substantially spiral outline to the 45 blades, from end to end.

The blades 3 are concave on one side, as indicated at 6, while the opposite faces thereof are convex, as indicated at 7, so that the blades will readily gather air on the concave sides and gradually feed it towards the outer ends of the blades, the volume of air at the outer ends of the blades being greater than at the inner ends thereof. At the same time the convex surfaces of the blades will create a vacuum adjacent one edge of the 55 blades, and thus gather a large volume of air to be picked up by the next succeeding blade, so that a greater volume of air will be expelled by the fan than can be created by the ordinary fan and without increasing 60 the dimensions of the fan over the ordinary fan structure.

The tilt of the blades is greater at their inner ends, the tilt gradually decreasing towards the outer ends of the blades so that 70 the extreme outer ends of the blades are more nearly flat, the degrees of tilt being clearly shown in Figures 3 to 6.

By this arrangement the inner portions of the blades serve partly as centrifugal flowing means which feed the flatter ends of the blades with air, said ends being calculated to drive the air thus fed, sideways with great force.

This fan is designed primarily for use in 80 connection with air cooled engines, the object being to direct a maximum blast of air without increasing the diameter of the fan blades, owing to the limited space in which to mount a fan, and it will be readily seen 85 that by shaping the blades as shown, a far greater volume of air will be thrown by the fan than could be obtained with the use of the ordinary fan structure.

While the description and drawings illustrate in a general way certain instrumentalities which may be employed in carrying the invention into effect, it is evident that many modifications may be made in the various details without departing from the scope of the 90 appended claims, it being understood that the invention is not restricted to the particular examples herein described.

I claim as my invention:

1. In a fan structure, a semi-globular hub, 100

a pair of blades attached thereto with their inner ends conforming to the outer curved surface of the hub, said blades being substantially concavo-convex in cross section
5 throughout their length the concavo-convex curvatures gradually decreasing in extent from the inner to the outer ends of said blades, one edge of the blades extending in a straight line from end to end with the
10 straight edge intersecting said hub substantially at the apex of the hub and the opposite edge of the blade intersecting said hub substantially at the base line thereof, the transverse width of the blades gradually decreasing from their point of connection with the hub to their outer ends.
15

2. In a fan structure, a semi-globular hub, a pair of blades attached thereto, the inner ends of said blades being substantially concavo-convex and the outer ends substantially straight in cross section, the concavo-convex curvatures gradually lessening from the inner to the outer ends of said blades, one edge of each blade extending in a straight
20 line from end to end and the opposite edge being gradually curved inwardly from its inner end, the inner end of the straight edge uniting with the hub substantially at the curved apex end of the hub and at one side
25 of the axis of the hub and the curved edge of the blade connecting with the hub at the opposite or base end thereof and on the opposite side of the axis of the hub.
30

3. In a fan structure, a substantially conoidal hub having a semi-oval surface, and blades radiating therefrom, the inner or connecting ends of said blades extending spirally of said hub from end to end thereof and transversely thereof substantially one-half
35 the diameter of the hub, one edge of each blade extending in a straight line from end to end and the opposite edge being gradually curved inwardly from its inner to its outer end with said curved edge arranged
40 spirally, whereby the extreme outer end of the blade will extend substantially in a straight line transversely of the axis of the hub and approximately in line with the apex or rounded end of the hub.
45

50 In testimony whereof, I have hereunto set my hand on this the 25th day of March, 1929,
A. D.

OWEN H. SPENCER.
